Attorneys.

UNITED STATES PATENT OFFICE

HEMSLEY B. MASSEY, OF GREENSBURG, PENNSYLVANIA, ASSIGNOR TO RAILWAY AND INDUSTRIAL COMPANY, OF GREENSBURG, PENNSYLVANIA, A CORPORATION OF PENNSYLVANIA

HIGH POTENTIAL SWITCH

Application filed March 14, 1930. Serial No. 435,899.

This invention relates to a high potential electric switch of the type used to break currents of high amperage.

It has been found that conductors or bus bars for carrying currents of 3000 amperes or higher are more efficient for alternating current if such conductors are arranged in groups. One such arrangement is in the form of a hollow square, the rectangular conductors being separated from each other. Cylindrical hollow conductors have also been used.

It is an object of this invention to provide a switch adapted for connection to conductors arranged in a hollow square or other hollow form, and which has the same desirable advantages as the conductors.

It is another object of the invention to provide a switch which can safely carry currents of high amperage.

Another object of this invention is to provide a switch which is simple and positive in its action, yet one by which very high pressure may be obtained between the relatively movable contacts.

These and further objects will be apparent from the following description when taken in connection with the accompanying drawings, wherein.

30. Fig. 1 is a side elevation of a switch embodying the invention,

Fig. 2 is a section on line 2—2 of Fig. 1,

Fig. 3 is a section on line 3—3 of Fig. 1.

Fig. 4 is an enlarged section of one portion of the movable and stationary contacts, and

Fig. 5 is a similar view at right angles to Fig. 4.

Referring to the drawings, a supporting base 1 is provided carrying spaced stationary insulators 2 and 3. The base 1 is so arranged that a track is formed for a reciprocating carriage 4 having rollers 5 thereon. As shown on the drawings, base 1 is made up of two spaced channel irons having the flanges thereof facing inwardly, rollers 5 riding on these flanges. Carriage 4 has mounted thereon an insulator 6 upon which is mounted the movable switch parts.

50. Insulators 2 and 3 carry stationary switch

members 7 and 8 which are hollow cylinders having their outer ends slotted and perforated for clamping engagement with conductors arranged as a hollow square. It will be clear that this switch is equally well adapted to conductors arranged in other configurations than a hollow square, or to hollow cylindrical conductors. It will be noted that stationary contact 7 is longer than contact 8 since the movable contact telescopes with contact 7 to open the switch.

Movable insulator 6 carries a U-shaped strap 9 which partially surrounds and supports the reciprocating contact 10 by a cross pin 11, said cross pin movable in slots 12 in contact 10. The ends of cross pin 11 project beyond strap 9 and carry equalizer bars 13. These equalizer bars 13 are normally positioned vertically, one on each side of the movable blade 10. Links 14 are pivoted to the ends of equalizer bars 13, these links being in turn connected to levers 15 for applying and releasing high pressure engagement between the stationary and movable contacts.

As seen in Figs. 1 and 2, the movable contact 10 telescopes over stationary contacts 7 and 8, moving to the right of Fig. 1 to open the switch. Each end of movable contact 10 is surrounded by a pressure-applying structure 16 which includes two straps 16 riveted or otherwise secured to the blade. These straps 16 have their ends perforated to receive bolts 17. These bolts 17 are hexagonal on one end as at 18 to receive a correspondingly angled socket 19 on levers 15, as seen in Fig. 2.

Two sectors 18 partially surround each end of movable blade 10, to apply pressure thereto. Each sector is formed in the shape of a T in cross-section for rigidity and strength. As seen in Fig. 2, each sector has a threaded end portion 19 to receive the threaded end of bolt 17, the other end 20 having an unthreaded opening to allow the passage of bolt 17. The sectors 18 conform generally to the outline of the movable contact 10 but they have four flattened portions 21 for contact with four raised portions 22 on the stationary contact, these portions 22 being shown as rivets.

which project beyond the outer surface of the contact.

In order to insure that the movable contact 10 telescopes over stationary contact 8 to a definite position before flattened portions 21 are clamped against 22, the following mechanism is provided. Adjacent the left hand end of movable contact 10 and within the same is secured a bracket 23 having backwardly extending arms 24 for pivotally supporting a latch 25. Latch 25 extends upwardly adjacent the cross pin 11 mounted on bracket 9, this end of the latch being notched as at 26 to engage cross pin 11. The other end of latch 25 has a slanting nose 27, and a spring 28 normally holds the latch 25 to the position shown in full lines in Fig. 5.

The operation of the switch is as follows. In the open position thereof pin 11 is at the right hand end of slot 12 in blade 10, and latch 25 is raised by spring 28 so that notch 26 of the latch engages cross pin 11. The equalizer bars 13 have been partially turned when the switch was last opened, so that levers 15 have been rotated to thus relieve pressure on sectors 18. If the reciprocable carriage 4 is now moved to the left, movement of pin 11 is transmitted to blade 10 by means of latch 25, blade 10 telescoping over contact 7 to a position bridging contacts 7 and 8.

When the end of contact 10 slips over contact 8 the sloping face 27 is engaged by contact 8 and latch 25 is turned about its pivot against the tension of spring 28. Notched end 26 of latch 25 thus releases pin 11 and further movement of carriage 4 advances pin 11 to the left hand end of slots 12, the blade 10 being prevented from further movement by the engagement of bracket 23 thereon with the edge of contact 8. The equalizer bars 13 are thus straightened to the position shown in Fig. 1, and moving levers 15 to their vertical positions. The turning of levers 15 turns bolts 17 to move segments 18 together at both the top and bottom, by means of the threaded engagement of bolts 17 with ends 19 of segments 18. The flattened portions 21 are thus pressed against rivets 22 under very high pressure, this high pressure contact occurring between movable blade 10 and both stationary contacts 7 and 8.

To open the switch the carriage 4 is moved to the right, thus moving pin 11 to the right hand end of slots 12. The equalizer bars 13 are thus twisted about pin 11 to rotate bolts 17, thus relieving the high pressure engagement of the contacts. When pin 11 reaches the end of its slot, latch 25 is positioned to move up to catch the notched end 26 over pin 11, as seen in Fig. 5, as soon as the other end of the latch has been released by the relative movement between blade 10 and contact 8. As soon as blade 10 leaves contact 8, the latch 25 thus moves up and the switch continues to move to open position, the parts be-

ing positioned for the next closing movement, since notch 26 holds pin 11 to the right hand end of the slots 12.

It will be understood that the flattened portions 21 and rivets 22 could be reversed, or these parts could be replaced by other mechanical expedients, such that high pressure contact is obtained between the movable and stationary contacts.

Various other modifications may be made without departing from this invention as set forth in the accompanying claims.

I claim:

1. In a high tension switch, two spaced stationary contacts, a cylindrical contact for bridging the same, means for moving said cylindrical contact axially to telescope the same over the stationary contacts, and means for clamping the movable contact into high pressure engagement with the stationary contacts.

2. In a high tension switch, two spaced stationary contacts, a reciprocable contact telescoping over said stationary contacts to bridge the same, clamping means surrounding said reciprocable contact for causing high pressure engagement thereof with the stationary contacts, and operating means for reciprocating said reciprocable contact and for operating said clamping means.

3. The structure as in claim 2 wherein said operating means has a lost-motion connection with said reciprocable contact.

4. The structure as in claim 2 wherein said operating means has a lost-motion connection with said reciprocable contact, and means for causing simultaneous movement of said reciprocable contact and said operating means in one direction of movement.

5. In a high tension switch, a stationary contact, a movable contact for telescoping engagement over said stationary contact, clamping means surrounding said movable contact for causing high pressure engagement thereof with the stationary contact, operating means for telescoping said movable contact over said stationary contact, and means for thereafter operating said clamping means.

6. In a high tension switch, a stationary contact, a reciprocable contact for telescoping engagement over said stationary contact, operating means for telescoping said reciprocable contact over said stationary contact, clamping means mounted on and movable with said reciprocable contact for causing high pressure engagement thereof with the stationary contact, and means connecting said clamping means with said operating means for clamping movement after said reciprocable contact has reached the closed position.

7. In a high tension switch, a stationary contact, a reciprocable contact for telescoping engagement over said stationary contact, operating means for telescoping said recip-

reciprocable contact over said stationary contact, a lost-motion connection between said reciprocable contact and said operating means, clamping means surrounding said reciprocable contact for causing high pressure engagement thereof with the stationary contact and operable upon relative movement between said reciprocable contact and said operating means, and a latch restraining relative movement of said reciprocable contact and said operating means until said contact has telescoped over said stationary contact when the switch closes.

8. The structure as in claim 7 wherein said clamping means includes a threaded member which is rotated to obtain this pressure.

9. The structure as in claim 7 wherein a spring returns said latch to its restraining position when the switch is opened.

In testimony whereof, I affix my signature.

HEMSLEY B. MASSEY.
